(57) **CLAIM**

The ornamental design for a hummingbird feeder, as shown and described.

DESCRIPTION

FIG. 1 is a perspective view of a hummingbird feeder showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is another perspective view thereof, but shown in a usage state in an environmental view; and,

FIG. 10 is an enlarged view of portion of FIG. 8.

The broken lines shown in FIG. 9 showing a stake illustrates environmental structure. All other broken lines illustrate portions of the hummingbird feeder that form no part of the claimed design.
